UNITED STATES PATENT OFFICE.

JACOB METZ, OF VERNON, ILLINOIS.

IMPROVEMENT IN WAGON-STANDARDS.

Specification forming part of Letters Patent No. 179,716, dated July 11, 1876; application filed June 12, 1876.

To all whom it may concern:

Be it known that I, JACOB METZ, of Vernon, in the county of Marion and State of Illinois, have invented a new and useful Improvement in Wagon-Standards, of which the following is a specification:

Figure 1 is a side view of one of my improved standards, part being broken away to show the construction. Fig. 2 is a view of the outer edge of the same. Fig. 3 is a side view, partly in section, of a modified form of the same. Fig. 4 is a vertical section taken through the line $\alpha\alpha$, Fig. 3.

Similar letters of reference indicate corresponding parts.

The object of this invention is to furnish improved standards or stakes for the bolsters of wagons, which shall be so constructed that they may be readily and quickly attached and detached, which shall be strong and durable, simple in construction, and inexpensive in manufacture, enabling a pair of bolsters to be ironed with much less labor, and at much less expense, than when they are ironed in the usual way.

The invention consists in the castings bolted to the bolster, and the base of the standard or stake, connected with the said castings by tongues and grooves, and with the bolster by a spring-bolt, as hereinafter fully described.

A represents a bolster, to the opposite sides of the ends of which are bolted iron castings B. The upper ends of the castings B project a little above the upper side of the bolster A, to receive the base C of the standard between them. The sides of the base C are connected with the upper ends of the castings B by tongues and grooves, as shown in Figs. 2 and 4. The grooves may be formed in the outer

sides of the base C, and the tongues upon the castings B, as shown in Fig. 2; or the upper ends of the castings B may be flush with the top of the bolster A, and have grooves in their outer sides to receive the tongues formed upon the downwardly-projecting sides of the base C, as shown in Fig. 4.

The base C may have an iron standard or stake, D, formed solid with it, as shown in Figs. 1 and 2; or it may be made hollow, as shown in Figs. 3 and 4, to receive a wooden standard or stake, which is secured to it by a bolt.

The base C is made with a solid outwardly-projecting brace or shoulder, which has a hole formed in its lower side to receive a bolt, E, to enter a hole in the upper side of the bolster A, to lock the said base in place. The bolt E is held down by a spring, F, placed above its upper end in the hole of the base C. To the upper end of the bolt E is attached a wire, G, that passes up through the spring F, and through a small hole in the base C, and terminates in a ring, to enable the bolt E to be readily drawn up into the base C, so that the base can be easily and quickly attached and detached when desired.

Having thus described my invention, I claim as new and desire to secure by Letters Patent—

The castings B, bolted to the bolster, and the base C, connected with the castings B by tongues and grooves, and with the bolster by a spring-bolt, E F G, substantially as herein shown and described.

JACOB METZ.
